UNITED STATES PATENT OFFICE.

LESTER J. SORTOR, OF DES MOINES, IOWA.

DESIGN FOR A DRILL-HOLE CLEANER OR SIMILAR ARTICLE.

58,691.

Specification for Design.

Patented Aug. 9, 1921.

Application filed February 9, 1921. Serial No. 443,709. Term of patent 14 years.

To all whom it may concern:

Be it known that I, LESTER J. SORTOR, a citizen of the United States, and a resident of Des Moines, in the county of Polk and State of Iowa, have invented a certain new, original, and ornamental Drill-Hole Cleaner or Similar Article, of which the following is a specification, reference being had to the accompanying drawing, forming part thereof.

The figure is a perspective view of my drill hole or similar article, showing my new design.

I claim:

The ornamental design for a drill hole cleaner or similar article, as shown.

Des Moines, Iowa, June 22, 1921.
